United States Patent Office

Des. 212,670
Patented Nov. 12, 1968

212,670

JUG

James L. Linn, Jr., Maumee, Ohio, assignor to Owens-Illinois, Inc., Toledo, Ohio, a corporation of Ohio

Filed Jan. 19, 1968, Ser. No. 10,227

Term of patent 14 years

(Cl. D9—44)

FIG. 1

FIG. 2

The characteristic features of this design reside in the configuration shown in full lines on the drawings.

I claim:

The ornamental design for a jug, substantially as shown and described.
